Des. 222,600
Patented Nov. 9, 1971

222,600

DISPLAY RACK FOR PERIODICALS

Stanley Wells, Bridgewater, Conn., assignor to
Mar-Line Displays, Inc., Mount Vernon, N.Y.

Filed July 2, 1970, Ser. No. 33,810

Term of patent 14 years

Int. Cl. D6—06

U.S. Cl. D80—9

FIG. 1.

FIG. 2.

FIG. 3.

FIG. 4.

FIG. 1 is a front perspective view of a display rack for periodicals embodying my new design;

FIG. 2 is a top plan view thereof;

FIG. 3 is a front elevational view thereof; and

FIG. 4 is a bottom view thereof.

The broken line representation of a support stand in FIG. 1 is for purposes of illustration only.

I claim:

The ornamental design for display rack for periodicals, substantially as shown and described.
